UNITED STATES PATENT OFFICE.

WALTER S. MOODY, OF SCHENECTADY, NEW YORK, ASSIGNOR TO GENERAL ELECTRIC COMPANY, A CORPORATION OF NEW YORK.

TRANSFORMER FOR ELECTRIC VEHICLES.

No. 876,988.

Specification of Letters Patent.

Patented Jan. 21, 1908.

Application filed August 10, 1904. Serial No. 220,160.

To all whom it may concern:

Be it known that I, WALTER S. MOODY, a citizen of the United States, residing at Schenectady, county of Schenectady, State 5 of New York, have invented certain new and useful Improvements in Transformers for Electric Vehicles, of which the following is a specification.

It is sometimes desirable to supply alternating current at one potential from stationary supply conductors to one winding of a transformer located on a movable vehicle, the other winding of the transformer furnishing alternating current of different potential to consuming devices located on or traveling with the vehicle. For instance, 10 the motors which propel electric railway cars may be driven by alternating current furnished to the low-pressure winding of a 15 transformer carried by the car, the high pressure winding of which is supplied with alternating current through stationary conductors and traveling contacts. In such a case the transformer used is subjected to somewhat violent mechanical vibrations, 20 particularly when the car is operated at high speed. This necessitates very careful construction, particularly when, as may be the case, the transformer is located beneath the 25 car body.

One of the objects of my present invention is the construction of a transformer which, while compact and of comparatively light weight, is well adapted to stand rough 30 usage such as may be experienced when the transformer is used on a traveling vehicle as above mentioned.

Another object of my invention is to so construct and arrange a transformer that 35 the heat generated in it may be rapidly dissipated without producing an undue rise in the temperature of the transformer.

I accomplish the last object of my invention partly by providing my transformer 40 with large and efficient heat-radiating surfaces, and partly through a construction by means of which the movement of the car generates air currents which engage the transformer to cool it.

50 The various features of novelty which characterize my invention are pointed out with particularity in the claims annexed to and forming a part of this specification. For a better understanding of my invention, 55 however, reference may be had to the ac-

companying drawings and description in which I have illustrated and described one embodiment of my invention.

Of the drawings, Figure 1 is an elevation of an electric car equipped with my invention, 60 Fig. 2 is a sectional elevation showing the arrangement of the conduit; Fig. 3 is a partial sectional elevation showing the hood at one end of the conduit; Fig. 4 is an elevation showing a trap which may be employed; 65 Fig. 5 is an elevation showing the removable conduit section; Fig. 6 is a perspective view of the transformer employed; Fig. 7 is an end elevation of the transformer with parts broken away and in section; Fig. 8 is a side 70 elevation of the transformer with parts broken away and in section; and Fig. 9 is a diagrammatic view showing an arrangement of the transformer, air compressor, and air reservoir.

75 Referring to the drawings, 1 represents a car of the ordinary type employed on high speed interurban electric railways. Trolley poles 2 located at each end of the car are alternately employed to take alternating current from an overhead conductor 3 at comparatively high potential, say 2,000 volts, and deliver it to the primary winding of a transformer 4 located below the car body. The secondary of the transformer supplies 80 current at a reduced potential, say 400 volts, to suitable motors mounted on the trucks 5. The return conductor of the primary system includes the wheels 6 and rails 7.

85 The core of the transformer, which is substantially of the type shown by the patent to Hall, No. 755,766, granted March 29, 1904, 90 comprises a central elongated horizontal leg or portion 8 and four legs or branches 9 which are similar to each other and are 95 spaced equally about the leg 8 and extend parallel therewith, and portions 10 which extend radially from each end of the leg or branch 8 to the ends of the legs or branches 9. The windings of the transformer surround the 100 central leg 8 and are located in the space between the legs 9 and end portions 10.

105 Each outer leg 9, corresponding end portions 10, and a quarter of the central leg or portion 8 of the core, are formed by two bundles 11 and 12 of laminæ of magnetic material. The bundles 11 are similar to the bundles 12 in that they are both rectangular in outline and formed with rectangular openings passing through them. The bundles 110

differ from each other, however, in the fact that the inner legs of the bundles 11 are substantially twice as wide as the corresponding legs of the bundles 12. The inner portions 5 of the four pairs of bundles 11 and 12 forming the core are assembled together as shown to form the central leg or branch 8 which is cruciform in cross-section.

Angle bars or plates 13 are placed in the 10 notched corners of the cruciform-shaped central leg or core 8 with their outer surfaces bearing against the sides of the laminæ. The inner legs of each pair of bundles 11 and 12 are clamped together by bolts 14 which pass 15 transversely through the bundles 11 and 12 and the adjacent flanges of the angle bars 13. As is clearly shown in the drawings, a cross-shaped ventilating space 14' extends through central leg or branch 8, the laminæ being 20 separated by spacers 15 for this purpose.

Each outer leg 9, which is substantially 25 rectangular in cross-section, is shown as somewhat wider in a direction measured perpendicular to the plane of lamination than is the central leg 8. This result is obtained by interleaving with the laminæ in the legs 9 corresponding to those in the inner legs or sides of the bundles 11 and 12 additional laminæ. Convexly curved members 16, 30 which may be formed of cast iron or the like, are located between adjacent sides of the adjacent core legs 9. The members 16 are formed with faces or surfaces at right angles to each other, which abut against the sides of 35 the adjacent core legs. The outer edges of these faces are flush with the outer edges of the core legs. The members 16 are formed with lugs 17 which are located adjacent to and project beyond the outer surface of the core 40 legs. Bolts 18 passing through apertures formed in the lugs 17 are employed to clamp each core leg between the adjacent members 16. As shown, the bolts 18 are located beyond the outer surface of the corresponding 45 core leg 9. The members 16 are formed on their outer surfaces with heat-dissipating ribs 16' which extend parallel to the length of the transformer and the line of motion of the car.

50 End plates or head members 20 are clamped against the ends of the core and the ends of the members 16 by bolts 21. The bolts 21 pass through and are positioned by apertured lugs 23 projecting for the purpose from the 55 inner surface of the members 16. To stiffen the construction, members 25 pivoted on the bolts 21 have formed in them threaded apertures in which are located bolts 26, the ends of which are forced against the angle bars 13. 60 The windings of the transformers comprise two concentric sections 30 and 31. The inner section 30 in turn comprises an inner primary coil 32 preferably formed out of a copper strip bent edgewise to form a helix, and 65 an outer secondary coil 33 which preferably

is also in the form of a copper strip or ribbon bent edgewise into a helix. A layer 34 of insulating material is placed between the coils 31 and 32 which may be taped together. The outer section 31 is formed of an inner 70 secondary coil 35 which is substantially similar to the coil 33 and an outer primary coil 36 which is substantially similar to the coil 32. The coils 35 and 36 are separated by a layer 75 of insulating material 37 and may be taped together as are the coils 32 and 33. The sections 30 and 31 are separated from each other to form a ventilating space by separators or space blocks 38.

The coils, which themselves possess considerable mechanical strength by reason of their construction, are locked tightly in place between the central leg 8 of the core and the outer leg 9 by strips or spacers 40 of insulating material. After the coils are firmly 80 locked in place by the spacers 40 the coils and core are several times dipped in a heavy insulating compound or paint to seal the core, the spacing strips and the coils into a rigid 85 mechanical structure. The exterior of the 90 shell formed by the legs 9 and members 16 is made water-tight by a coating of water-proof paint or the like.

The transformer is placed beneath the car body with the legs 8 and 9 extending parallel 95 to the direction of movement of the car and is supported by a skeleton frame or cradle 41 comprising a number of substantially U-shaped wrought iron bars 42 which are connected at their upper ends by rails 43. Notches 100 are formed in the lugs 17 to receive and position the U-shaped members 42. Bolts passing through the U-shaped bars 42 and rails 43 are employed to secure the cradle to 105 the car structure.

As is clearly shown in the drawings, the end plates of the transformer are formed each with a cylindrical flange or lip 45 which surrounds an opening 46 centrally located in the end plate. To stiffen the structure a 110 number of bars 47 extend transversely across the openings 46. Conduits 48, the bodies of which are located between the floor-beams 48' of the car, extend from points adjacent the ends of the transformer to points adjacent the ends of the car. A pipe or conduit section 49 is employed to connect each end of the transformer to the adjacent end of the corresponding conduit. The conduit section 49 may be hinged to the conduit body as 115 shown at 49' and provided with a collar 50 which may be locked removably about the flange 45 by thumbscrews 51 as shown in Fig. 5. A hood or funnel 52 is connected to the outer end of each conduit. It will be 120 easily understood that the movement of the car will cause air to be taken in by the forward funnel and delivered through the forward conduit 48 and section 49 to the interior of the transformer from which it will escape 125 130

through the rear section 49, conduit 48, and funnel 52. The passage of air through the transformer will, of course, remove heat generated in the transformer.

5 To prevent the entrance of dirt into the transformer a screen 53 is placed at the mouth of each funnel. Traps 54 (see Fig. 4) are preferably provided in the conduits at each side of the transformer, into which the 10 bulk of the dirt passing the corresponding screens is collected. The traps 54 also serve to prevent rain and snow from entering the transformer. By making the conduit sections 49 removable as described, the interior 15 of the transformer can be readily cleaned of any dirt which may accumulate in it by the use of a compressed air cleaning device.

As shown diagrammatically in Fig. 9 of the drawings, I may connect the intake pipe 20 56 of the air compressor 57, which fills the reservoir 58 with air for the operation of the car brakes, to take air from the interior of the transformer. The pipe 56 may be connected to the middle of the upper cover 25 plates 55 by connections 55' as shown. This increases the air circulation through the transformer in an advantageous manner as the brakes are used most frequently and consequently the air pumped most rapidly by 30 the compressor when the car is running at comparatively low speed and when therefore the circulation produced by the motion of the car proper is least noticeable.

The transformer construction which I have 35 herein described and illustrated in detail possesses many advantageous features of construction and arrangement which are not limited to use for any particular purpose or in any particular arrangement. The construction, however, embodies features which are particularly useful when the transformer is to be mounted beneath a car as shown in Fig. 1. The design is one in which the 40 length of the transformer may be made comparatively great with reference to the other dimensions of the transformer. This is of importance in view of the limited space in which the transformer must be supported.

It is frequently desirable to make a transformer air-cooled rather than oil-cooled to 45 economize space by dispensing with the oil-containing casing or for other reasons. With the construction shown, an air-cooled transformer is obtained in which the windings are 50 thoroughly protected and incased while at the same time the casing employed is such as to leave a very large portion of the core surface exposed to the outside air, thus facilitating heat radiation. As shown, the upper 55 and lower legs 9 of the corresponding end portions 10 and portion of leg 8 are laminated in vertical planes, while the remainder of the core is laminated in horizontal planes. It will thus be observed that all the electrical 60 and magnetic advantages to be obtained by

laminating the core are possessed by this construction, while at the same time the arrangement is such that the laminating of the core in vertical planes does not weaken that portion of the core against up and down vibration, which is best able to maintain the 70 rigidity of the core against such vibrations, while the laminating of the remainder of the core does not weaken the core against horizontal vibrations.

Certain features of invention shown and described, but not claimed herein are claimed in my co-pending application, Serial No. 322,016, filed June 16, 1906.

What I claim as new, and desire to secure 80 by Letters Patent of the United States, is,—

1. In combination, a transformer core comprising a central leg or branch, a winding placed about said central leg or branch, a return magnetic circuit for said leg or branch 85 comprising a number of legs arranged about the central leg and winding, and covers for the winding secured between adjacent branches of said return circuit.

2. In combination, a transformer core 90 comprising a central leg or branch, a winding placed about said central leg or branch, a return magnetic circuit for said leg or branch comprising a number of legs arranged about the central leg and winding, and covers for 95 the winding secured between adjacent branches of said return circuit, said covers being provided with heat-radiating ribs.

3. In a transformer having a core and a winding, a casing surrounding said winding 100 formed of alternating core portions and cover members.

4. In a transformer having a core and a winding, a casing surrounding said winding 105 formed of alternating core portions and cover members, said cover members being provided with heat-radiating ribs.

5. A transformer core, comprising a central leg or branch about which windings are placed, a return circuit for said leg or 110 branch comprising a number of legs parallel to the first-mentioned leg and arranged about the first-mentioned leg, and cover plates for the windings located between adjacent branches of said return circuit.

6. In a transformer, a core comprising 115 laminated portions separated from each other by spaces, and cover members connecting adjacent core portions to form a casing.

7. In a transformer, a central leg or branch of magnetic material, windings surrounding said central branch, and a return circuit for said central branch formed of a number of parts which are arranged about said central 125 leg or branch, each of said parts being formed of laminated material, some of said parts being laminated in different planes from other of said parts, each of said parts being connected with adjacent parts by a support- 130

- 4
- ing member, the supporting members and parts being secured together to form a shell surrounding said windings.
8. In a transformer, a central member about which windings are placed, and a divided magnetic return circuit therefor comprising parts located about said centrally formed member, said parts being laminated perpendicularly to their outer surfaces, supporting members extending one between each pair of adjacent sides of adjacent parts, and means for securing said parts together in a rigid structure without impeding the circulation of a cooling fluid against the outer surfaces of said parts.
9. In combination, a movable vehicle and a transformer carried thereby, said transformer comprising a core, a winding, and a casing surrounding said winding formed of alternate core portions and cover members, said cover members being provided with heat radiating ribs extending parallel to the motion of the vehicle.
10. A transformer core comprising a central leg or branch about which windings are placed, a return circuit for said leg or branch, comprising a number of legs parallel to and arranged about the first mentioned leg, and cover plates for the windings located between adjacent branches of said return circuit, said cover plates being provided with heat radiating ribs or projections extending parallel to the legs.
11. In a transformer, a core comprising laminated portions separated from each other by spaces, and cover members engaging adjacent core portions to form a casing, said cover members being provided with heat radiating ribs.

In witness whereof I have hereunto set my hand this 5th day of August, 1904.

WALTER S. MOODY.
